PORTABLE ROOM HUMIDIFIER

Dewey M. Dow, Toledo, Ohio, assignor to Air-Way
Electric Appliance Corporation, Toledo, Ohio,
a corporation of Delaware

Application July 15, 1949, Serial No. 105,009

6 Claims. (Cl. 261—29)

1

This invention relates to humidifiers but more particularly to a portable humidifier for room use.

An object is to produce a humidifier for room use by which a current of air from the room is constantly forced through a liquid screen in contact with liquid for increasing the moisture content of the air within the room.

Another object is to produce a simple and inexpensive humidifier which, by means of a motor driven fan, air is kept in constant circulation and brought into contact with water and which incorporates a fountain thereby providing a unit which is not only satisfactory for humidifying the air but also presents a pleasing and attractive appearance.

A further object is to produce a room humidifier which has the new and improved features of construction, arrangement and operation herein-after described, and for purposes of illustration but not of limitation, an embodiment of the invention is shown in the accompanying drawing, in which

Figure 1 is a vertical sectional elevation of the humidifier;

Figure 2 is a transverse sectional view on the line 2—2 of Figure 1;

Figure 3 is a transverse sectional view on the line 3—3 of Figure 1;

Figure 4 is a vertical sectional view on the line 4—4 of Figure 1; and

Figure 5 is a vertical sectional view on the line 5—5 of Figure 1.

The illustrated embodiment of the invention comprises a humidifying device particularly for room use, which comprises a standard having legs 10 of any suitable height having floor engaging feet 11 and held together by a pair of annular metallic lower and upper bands or rings 12 and 13, respectively, which are secured, as by rivets, to the legs 10. Secured to the inside of the legs 10 in the region of the band 12 by rivets 14 are a series of equi-distantly spaced ledges 15, on which rest laterally extending arms 16 which are secured, as by welding, to the bottom of a tank 17. The end portions of the arms 16 have a pair of downwardly extending flanges 18 which are disposed on opposite sides of the respective ledge 15 and militate against the arms 16 from slipping off from the ledge 15.

The tank 17 is of substantial depth and provides a water reservoir for the humidifier. On one side of the tank 17 is a spout 19 which projects laterally slightly beyond the legs 10 and provides a convenient filling opening for replen-

2

ishing the water level within the reservoir. Adjacent the bottom of the tank 17 is a pump housing 20 in which is disposed a pump 21 of any suitable or well-known structure. The pump housing 20 has an opening (not shown) to the inside of the tank 17 and has an outlet to which a copper tube 22 is connected, the latter extending upwardly and above the tank 17 and is connected by a rubber hose 23 to a fitting 24 which connects to an upright tube 25 terminating in a nozzle 26 from which the water is discharged in fountain fashion.

The pump housing 20 is connected to the lower end of an upright tube 27, the upper end of which is rigid with a motor support 28 in which an electric motor 29 seats. Disposed within the tube 27 is a shaft 30, the lower end of which is operatively connected to the water pump 21 and the upper end of which is suitably connected to the armature shaft of the motor 29 so that the motor 29 thus drives the pump 21.

It will be observed that the electric motor 29 is disposed above the upper end of the tank 17 and is supported by a plurality of equi-distantly spaced tubular rods 31 which extend radially with respect to the motor, the inner ends of the rods being engaged in sockets in the motor support 28 and secured in place by set screws 33. The outer ends of the tubular rods 31 rest in a rubber block 34 which are supported on ledges 35 secured to the legs 10 or band 13. Each rubber block 34 has a U-shaped cut-out 34' on its inner face in which the adjacent end of the tubular rods 31 rest. Thus it will be apparent that the vibration from the electric motor 29 is cushioned by the rubber blocks 34.

Formed in the upper side of one of the tubular rods 31 is a pair of longitudinally spaced openings to receive the cord 36 for delivering electrical current to the motor 29. This is to enable the cord to be kept dry and out of contact with the water passing over the tube. A flange fitting 37 is disposed adjacent each of the openings into such tube in such position that any liquid from above will not enter these openings but will flow along the flanges of the fittings and into the tank 17. This will be more fully explained hereinafter.

For holding the copper tubing 22 in its upright position, a collar 38 embracing the tube is secured to one of the tubular rods 31 in any suitable manner as by soldering or welding. Since the tubular rods 31 are cushioned in rubber and since the upper end of the tubing 22 is connected to a rubber tube 23, vibrational noises are obviated.

Supported on ledges 39 formed in the upper portion of the rubber blocks 34 is a ring-like pan 40 having an outer wall 41 which curves upwardly and outwardly, terminating in a downwardly extending flange 42 and a relatively short upright inner wall 43 spaced a relatively short distance from the outer wall 41. Secured, as by welding, to the bottom wall of the pan 40 is a sleeve 44 which is spaced from and parallel to the inner wall 43 but extends a short distance above the upper end of the sleeve 43. The lower end portion of the sleeve 44 provides a trough 45 in the bottom of which is an annular series of relatively closely spaced openings 46. The construction is such that water which fills the pan to the height of the inner wall 43 can overflow into the trough 45 and from the trough 45, the water trickles into the tank or reservoir 17 through a foraminous metallic screen 47. The screen 47 is in the form of a cylinder and is provided in its upper end with a series of grommets 48 through which the tubular rods 31 extend. In this manner, it will be apparent that the screen cylinder 47 is supported in vertically disposed position by the tubular rods 31. Within the sleeve 44 is disposed a radial bladed fan 49 connected to be driven by the electric motor 29.

Supported slightly above the mouth of the pan 40 is a trough 50 which is of less diameter than the mouth of the pan 40 and has a dome-shaped central portion 51, a trough portion 52 and a downwardly and outwardly inclined overflow wall 53 which terminates in a relatively shallow trough 54 at the outer edge, the underside of the trough 54 being provided with an annular series of closely spaced openings 55 arranged to allow water to drip therefrom into the pan 40. The trough 40 rests upon a plurality of downwardly and outwardly inclined legs 56 which have rubber feet 57 engaging the upper edge of the sleeve 44. The upper ends of the legs 56 curve downwardly from the trough and are riveted to a depending cone-shaped baffle 58.

The fitting 24 extends through and is secured to the dome-shaped portion 51 of the trough and mounted on the upright tube 25 are three pans or troughs 59, 60 and 61 of varying sizes, the upper one being the smallest and the bottom one being the widest. This enables water in fountain fashion from the nozzle 56 to overflow successively from the pan 61 through and into the pans 60, 59 and into the trough 52.

A screen cylinder 62 surrounds the legs 10 between the rings 12 and 13 and provides a grill or enclosure for the side of the apparatus.

In operation, the water is pumped from the tank 17 by the pump 21 through the tube 22, rubber tube 24 and vertical tube 25 from which it issues in fountain fashion from the nozzle 26. The water then overflows successively from the pans 61, 60 and 59 and into the relatively large trough 52. From the trough 52 the water passes down the outwardly inclined wall 53 and then drips from the trough 54 into the pan 40. From the pan 40, the water overflows the inner wall 43 and then passes from the trough 45 down along the screen cylinder 47 and returns to the tank or reservoir 17. The radial bladed fan 49 draws in air from the outside through the screen cylinder 62 and through the screen cylinder 47 where it is brought into intimate contact with the water which passes thereover. From the inside of the screen 47 the air is forced upwardly and due to the cone baffle 48 is forced outwardly and leaves the apparatus in the space between 75 pan and in contact therewith, legs connected

the trough 54 and the outwardly flaring wall 41. Here the air passes through a water screen and picks up additional moisture. Thus the stream of air is brought into contact with two curtains or screens of water as well as coming into contact with the surface of the water in the tank 17 and in the pan 40. This enables the air to pick up a substantial amount of moisture.

From the above description, it will be manifest that I have produced not only an exceedingly satisfactory room humidifier but one which is attractive and inviting, the fountain effect creating constant source of interest. The vibrational parts are mounted in rubber so that the noises and rattles are virtually eliminated, the only sound being the bubbling and trickling of the water. The arrangement is such that the pan 40 may contain plant life, a constant supply of water being maintained for that purpose.

It is to be understood that numerous changes in details of construction, arrangement and operation may be effected without departing from the spirit of the invention especially as defined in the appended claims.

What I claim is:

1. A humidifier comprising a liquid reservoir, a ring-like container having a relatively low inner wall spaced above said reservoir, said inner wall being arranged to enable liquid overflowing same to drop into said reservoir, a pan spaced above said container and arranged to enable liquid to drop into said container, a pump and connections for forcing liquid from said reservoir to said pan, a fan inside the inner walls of said container, an electric motor common to said pump and fan, a bracket supporting said motor, arm means radiating from said bracket, and a rubber-like mounting for supporting the outer ends of said arms, said mounting also serving to support said container.

2. A humidifier comprising a liquid reservoir, a ring-like container having a relatively low inner wall and a relatively high outer wall, said container being spaced above said reservoir, a sleeve spaced from said inner wall and having a perforated trough at the lower end secured to the container whereby liquid overflowing the inner wall drops into said trough and from said trough liquid drops into the reservoir, a screen cylinder having its upper edge adjacent the perforated bottom of said trough to enable liquid to travel along said screen to the reservoir, a pan spaced above said container and arranged to enable liquid therefrom to drop into said container, a pump and connections for forcing liquid from said reservoir to said pan, a fan for creating a stream of air from the outside between the reservoir and container and then to the outside through the space between the container and said pan, and motor means for driving said fan and pump.

3. A humidifier comprising a liquid reservoir, a ring-like container having a relatively low inner wall and a relatively high outer wall, said container being spaced directly above said reservoir, a sleeve inside of said inner wall and extending thereabove, a trough on the lower end of said sleeve connected to said container, said trough being perforated to enable liquid to drop therefrom into said reservoir, a pan spaced above said container and having a trough on the outer rim thereof, said trough being perforated to enable liquid to drop therethrough into said container, a cone-like baffle directly beneath said 75 pan and in contact therewith, legs connected

to said baffle and inclining downwardly, the outer ends of said legs resting against the upper edge of said sleeve whereby the legs support the baffle and said pan, a fan disposed inside said sleeve, a pump and connections for forcing liquid from said reservoir to said pan, and an electric motor common to said fan and pump to drive same.

4. A humidifier as claimed in claim 3, comprising a plurality of graduated pans cooperating with said first pan to provide a fountain effect, a tube providing a support for said graduated pans, and a nozzle at the upper end of said tube.

5. A humidifier comprising a standard, a liquid reservoir supported by said standard, a pump within said reservoir, an electric motor above said reservoir, a shaft depending from said motor and operatively connected to drive said pump, a bracket for supporting said motor, said bracket having a depending tube enclosing the pump driving shaft, a plurality of sockets arranged radially of said bracket, tubular arms having their inner ends connected to said sockets respectively, one of said tubes having spaced holes to receive the cord for said motor whereby the cord enters one hole, extends through the respective tube and out through the outer hole, flange means adjacent said holes respectively for militating against liquid entering same, rubber blocks carried by said standard for supporting the outer ends of said rods, a ring-like container spaced above said reservoir, said container having a relatively low inner wall and a relatively high outwardly flared outer wall, a ledge on said rubber mounting for supporting said container, a sleeve spaced from the inner wall of said container and having a perforated trough at the bottom thereof connected to said container, said trough receiving liquid overflowing from said container, a screen cylinder carried by said radial tubes and disposed directly beneath said trough to enable liquid to travel along same, and into said reservoir, a pan spaced above said container and having a perforated trough at the rim thereof to enable liquid to drop into said container, a fan within said sleeve and driven by said electric motor, a cone-shaped baffle beneath said pan for causing the

air to flow outwardly, legs connected to said cone and inclining downwardly with the outer ends thereof resting upon the upper edge of said sleeve, said legs supporting said cone and said pan, a tube fixed to said pan and extending upwardly therefrom, a plurality of graduated pans carried by said tube, a spout on the upper end of said tube, tube means connecting said tube and said pump to enable said pump to force liquid from said reservoir through said tube means and tube and discharge same from said spout, and a screen cylinder about said standard enabling air to be drawn therethrough by said fan.

6. A humidifier comprising a liquid reservoir, a 15 ring-like container spaced above said reservoir, means providing a perforated trough at the lower end of said container to enable liquid overflowing therefrom to drop into the trough, foraminous sheet material having its upper edge adjacent a perforated bottom of said trough to enable liquid to travel along the same to the reservoir, a pan spaced above said container and arranged to enable liquid therefrom to drop into said container, a pump and connections for forcing liquid from said reservoir to said pan, a fan for creating a stream of air from the outside between the reservoir and container and then to the outside through the space between the container and said pan, baffle means for directing the air from said fan in a lateral direction, and motor means for driving said fan and pump.
